[57] CLAIM

The ornamental design for a merchandise display, as shown and described.

DESCRIPTION

FIG. 1 is a perspective view showing my new design, with a housing and display panels shown in broken lines for purposes of illustration only and forming no part of the claimed design.

FIG. 2 is a front view thereof.

FIG. 3 is an enlarged top plan view taken substantially along the line 3—3 of FIG. 2.

FIG. 4 is a perspective view of one of the panel display racks, shown separately for clarity of illustration.

FIG. 5 is an enlarged side view showing one panel of the rack shown in FIG. 4, shown broken away for convenience of illustration.

FIG. 6 is an enlarged side view similar to FIG. 5 showing a second embodiment of a panel that may be used in my new design; and,

FIG. 7 is a front view similar to FIG. 2 showing an alternate embodiment of my new design, with a housing and display panels shown in broken lines for purposes of illustration only and forming no part of the claimed design, it being understood that all the other surfaces are the same as the first embodiment shown in FIG. 1—5.
